UNITED STATES PATENT OFFICE.

MARGUERITE PASSERIEUX, OF ST. LOUIS, MISSOURI.

BABY-WALKER.

Specification of Letters Patent. Patented Sept. 21, 1915.

1,154,543.

Application filed May 22, 1912. Serial No. 698,948.

To all whom it may concern:

Be it known that I, MARGUERITE PASSERIEUX, a citizen of the United States, residing at St. Louis and State of Missouri, have invented certain new and useful Improvements in Baby-Walkers, of which the following is a specification.

This invention has relation to a baby walker adapted to remain stationary as the child walks to and fro. Therefore, it will be seen that the main object of this invention is to provide a baby walker that will obviate injury to the child as the child is held within certain limitations. At the same time the child is afforded sufficient walking space, and, being amused by bells provided at the top of the walker, the child will make no effort to get beyond the limitations of the same.

20 A further object of my invention is to provide a baby walker that will be efficient in operation and may be manufactured inexpensively.

Reference being had to the drawings: Figure 1 is a side elevation of my baby walker ready for use, the dotted lines indicating the position of the trays at the end of the chair, when in lowered position. Fig. 2 is a top plan view of the baby walker, ready for use. Fig. 3 is a bottom plan view of the baby walker in readiness for use. Fig. 4 is an end elevation. Fig. 5 is a view of the baby walker as it appears when in folded condition, the dotted lines indicating the position of the braces at such time. Fig. 35 6 is a vertical, transverse section on line 6-6 of Fig. 2.

Referring more particularly to the drawings, in which like numerals designate like parts throughout my invention is described as follows: My baby walker consists of a rectangular frame 1, at each end of which is a pair of legs 2, said legs being connected to the frame by hinges 3. When the walker is in use the rule joint braces 4 hold the legs in position. Said braces being each pro-

vided centrally with a hinge 5, they are foldable in one direction only, see dotted lines in Fig. 5. Provided within the frame 1 and slidably held in longitudinal grooves 1' 50 therein is a centerpiece 6, said centerpiece being provided with an opening 7 therein occupied by a child when walking, said opening being of sufficient size to allow the child to turn around freely therein. 55

8 are bells mounted beneath the frame 1 and against which hammers 9, carried by the centerpiece, are adapted to strike when the centerpiece reaches each end of the baby walker. This bell will amuse the child and serves as a means for preventing the child from attempting to leave the walker. A tray 10 is hinged to each end of the frame 1, said trays being held in raised position, when desired, by pivoted supports 11. 60 65

Having described my invention, what I claim as new, is:

1. A baby walker comprising a frame, a centerpiece slidably mounted thereon, bells mounted upon the frame and located at the 70 ends of the path of movement of the centerpiece, and hammers carried by the centerpiece and adapted to strike the bells when the centerpiece arrives at the ends of its path of movement in the frame. 75

2. A baby walker comprising a frame element, a centerpiece element slidably upon said frame element, a bell carried by one of said elements, and a hammer carried by the other of said elements, the said hammer and 80 bell being adapted to be brought into engagement with each other during the sliding movement of the centerpiece relative to the frame.

In testimony whereof I affix my signature 85 in presence of two witnesses.

MARGUERITE X PASSERIEUX.
